UNITED STATES PATENT OFFICE

2,455,226

VACUUM SCUFFLER.

Harold Cartmell and Cecil Carey, Chilliwack,
British Columbia, Canada.

Application April 13, 1945, Serial No. 588,190

7 Claims. (Cl. 61—5)

1

This invention relates to new and useful improvements in a vacuum scuffer. Its primary object is to devise and construct a simple and easy to manufacture vacuum scuffer.

A further object of the invention is to provide a scuffer that will loosen sand and gravel from the bottom of a river and which will be carried away elsewhere by the current, thus providing a clean channel for navigation purposes.

With these and other objects in view that may appear while the description proceeds the invention consists in the novel construction and arrangement of parts as hereinafter more specifically set forth, claimed and shown in the accompanying drawings forming part of this application and in which:

Fig. 1 is an end view of the vacuum scuffer lying on the bottom of a river and the stream flowing in the direction indicated by arrows;

Fig. 2 is a plan view of the apparatus as it lies on the bottom of a river showing the cable also known as drag anchor;

Fig. 3 is a front view of the vacuum scuffer;

Referring more in detail to the drawings in which similar reference characters designate corresponding parts throughout the several views it will be seen the invention comprises a frame 5, on which is mounted angularly a series of blades 6. At both ends 7 and 8, of frame 5, is mounted a shoe. Where the current of the stream hits the upper blades it forces the vacuum scuffer down stream and holds it on bottom, while the current hitting the lower blade is forced on the bottom of the river and will remove sand and gravel, carry it away and deposit it elsewhere. The shoes 7 and 8, are to provide easy traction for the apparatus. A certain distance must be maintained between the bottom of the river and the underside of the scuffer. The shoes on the scuffer will regulate the volume of water passing on the underside of the scuffer blades. The angle of the blades 6, may be varied to allow for different forces in different streams. The stronger the current the lesser the angle between blades may be, as it will be easily carried down stream as it may be readily seen the device uses the river current for power. The length of scuffer and also of blades may vary according to work being done.

The slots 9, in frame 5, are to allow an adjustment for the angle of blades 6. Blades are held in the longitudinal slots by a quick release device 10. The cable or drag anchor 11, is set in one of a plurality of holes 12, on frame 5, and when set in the top hole, the scuffer would be

held down to a greater extent than when placed in either of the other holes. Where the stream may not be sufficient to remove the silt after the blades have been arranged to the greatest possible angle, the drag anchor 11, may be lowered to the hole closest the bottom of the river allowing the greatest portion of the scuffer to be above retaining point on the anchor drag. Such an arrangement will cause the scuffer to tilt forward thus increasing the angle between lower blade and bottom of river causing the current to strike harder on the gravel and sand to be removed. A weight 13, is securely fastened at the end of drag anchor, from where it derives its name so that the movement of scuffer may be considerably slowed down thus permitting the current to strike longer on the same spot and removing more sand and gravel.

In lieu of an anchor the scuffer's speed could be efficiently controlled by a donkey on a scow. This may even be preferable when the river bottom is obstructed by snags, stones and boulders.

The anchor and scuffer are dropped into the water at the up stream end of the sand bar, the current running over the upper blades forces it down stream while the current running below the bottom blades will remove the sand and the anchor will control the speed of the apparatus. After the silt is dislodged the vacuum behind the two blades sucks it up to where it is met and carried away by the water that has passed over the upper blades. A floating buoy may be attached to the anchor and another to the scuffer so that they can be picked up after having moved down over the bar and into deep water. Rudders may sometimes be used on the scuffer where current is extremely strong but are not always necessary.

It is believed that the construction and advantages of the invention may be apparent from the foregoing paragraphs taken in conjunction with the accompanying drawings without further detailed description.

While the preferred embodiment of the invention has been disclosed it is understood that minor changes in the details of construction, combination and arrangement of cooperating parts may be resorted to within the scope of what is claimed without departing from the spirit of the invention.

We claim:

1. A dredging device adapted to be submerged in a body of water in the path of its current comprising a frame composed of upright rectangular end members disposed in spaced relation par-

allel to the flow of current, a pair of vertically spaced deflector blades extending longitudinally between and connected to said end members, said blades being inclined transversely in opposite directions with their converging edges facing the flow of the current.

2. A device of the character described in claim 1 wherein rockers are provided on the upper and lower edges of the end members to rockably support the frame on the bed of the water.

3. A device of the character described in claim 1 wherein said blades are adjustably mounted to change the degree of inclination.

4. A dredging device adapted to be submerged in a body of water in the path of its current comprising a frame composed of spaced upright end members disposed in parallel relation to the flow of the current and a V-shaped baffle member extending horizontally between the end members with its apex facing the flow of current whereby the current is diverted in an upward and downward direction.

5. A device of the character described in claim 4 wherein rockers are provided on the upper and lower edges of said end members to rockably support the frame on the bed of the water.

6. A device of the character described in claim 4 wherein said baffle is adjustably mounted in said frame.

7. A dredging device adapted to be submerged in a body of water in the path of its current comprising a frame composed of spaced upright end members disposed in parallel relation to the flow of the current, rockers on the upper and lower edges of said end members rockably supporting said frame on the bed of the water, a V-shaped baffle extending horizontally between said end members with its apex facing the flow of current whereby the current is diverted in an upward and downward direction, and a drag anchor adjustably connected to the front of said frame to secure the frame in a vertical or tilting position.
